BUSHING STRUCTURE

Filed June 25, 1928

2 Sheets-Sheet 2

UNITED STATES PATENT OFFICE

HENRY SCHWARTZ, OF CHICAGO, ILLINOIS, ASSIGNOR TO BARREL FITTING AND SEAL CORPORATION OF AMERICA, OF CHICAGO, ILLINOIS, A CORPORATION OF ILLINOIS

BUSHING STRUCTURE

Application filed June 25, 1928. Serial No. 287,981.

This invention relates to a bushing structure and a sealing means therefor and has special reference to a structure such as is used as a bung for metallic barrels and other containers usually employed in storing or shipping oils or other liquids or semi-liquids.

More, particularly, this invention relates to a bung or plug which is so constructed and arranged as to effectively prevent a leakage of the liquid or semi-liquid from the container during the shipping or storage thereof and means for preventing access to the bung or plug in order to guard against an unauthorized opening of the barrel or container with-
15 out such opening being detected.

In the embodiments illustrated and herein-after described in this application, the bung is cast or otherwise formed with the usual tool engaging formations on the outer face 20 thereof and is externally threaded adjacent the inner face thereof to engage an internally threaded bushing of the container or barrel. The means for preventing access to the liquid in the barrel or the container without such 25 access being detected comprises a lug preferably formed integrally with the bung or plug, the lug having a weakened portion preferably at the point of intersection with the bung in order that an unauthorized displacement
30 of the bung will break the lug at the weakened portion. When it is noted that the lug has been thus broken off, the purchaser or user will have due notice that this container has been tampered with.

35 In addition to the above-noted construction, a tag or seal is assembled together with the lug as a further indication, when displaced, that the barrel has been tampered with. A tag of this nature is usually provided on containers for oil and other substances for denoting the quality thereof together with the shipper's number and such other information as the refiner should desire to have placed thereon. It is apparent that the middle man 40 or jobber has an opportunity to substitute a tag denoting a grade of oil of higher quality for the tag originally placed thereon by the refiner and thus defraud the dealer and ultimate consumer should the latter not be given 45 due notice of such tampering. The present
50

invention contemplates preventing this practice.

Other objects and advantages will herein-after be described and for a better understanding of the nature and characteristics and 55 scope of this invention, reference may be now had to the following description and accompanying drawings; in which latter:

Figure 1 is an end elevational view of a portion of a barrel head showing the bung in 60 an assembled relation with the bushing structure therein;

Fig. 2 is a central sectional view taken on the line 2—2 of Fig. 1;

Fig. 3 is a plan sectional view of the above 65 structure taken on the line 3—3 of Fig. 2;

Fig. 4 is a fragmentary view similar to Fig. 2 of a modified form of this invention;

Fig. 5 is a fragmentary plan sectional view of the modification of Fig. 4 taken on the 70 line 5—5 of Fig. 4;

Fig. 6 is an end elevational view of a portion of a barrel head similar to Fig. 1 showing a still further modification of this invention;

Fig. 7 is a central sectional view taken on 75 the line 7—7 of Fig. 6;

Fig. 8 is a plan sectional view taken on the line 8—8 of Fig. 7;

Fig. 9 is a fragmentary view of a portion of the bung of Fig. 6 inserted in the bushing 80 of the barrel and corresponding to the view shown in Fig. 7 although showing a modified form of wedge;

Fig. 10 is an underneath plan view taken on the line 10—10 of Fig. 9; and 85

Fig. 11 is a perspective view of the tag disclosed in Fig. 6.

Referring to the drawings, and more particularly to Figs. 1 to 3, inclusive, thereof, a barrel head or supporting wall 10 of a container is shown and is preferably formed of sheet steel. A collar portion 11 having a flange 11a extending at substantially right angles thereto is preferably formed integral- 90 ly with the head 10 and projects outwardly 95 from the interior of the barrel or the container to form a socket.

The side walls or collar 11 of the socket are preferably polygonally shaped and receive therein the main body portion 12 of a similar 100

5 peripheral contour. Although it is preferable to provide a polygonally shaped socket in which to contain the main body portion 12, it is to be understood that any outwardly extending socket of any particular contour 10 may be employed, although it is preferable that the socket have a non-circular peripheral contour in order to prevent the main body portion 12 from turning therein. The 15 main body portion 12 is preferably formed of an internally threaded casting or stamping which may be made of malleable iron or analogous substances.

15 In the particular construction shown in the various modifications of this invention, the edges or collar portion 11 of the socket are tapered, the taper converging rearwardly or inwardly from the outer surface of the container towards the inside side of the container; that is, the outer diameter at the bottom 20 of the main body portion 12 is smaller than the outer diameter at the top portion thereof. The collar portion 11 of the socket is formed to snugly engage the tapered edges 25 of the main body portion to form a securing means of a dovetail cross section, the flanged portion 11a, extending from the upper end of the collar portion, engaging the face of the main body portion.

30 The bushing structure just described and the particular method of forming the engaging walls of the socket with the internally threaded body portion 12 are more fully described in my co-pending applications, 35 Serial Nos. 217,031 and 239,207, respectively. However, this particular construction is shown for the purpose of illustrating a preferable form of bushing structure and it will be understood that the plug or bung herein- 40 after described may be associated with any bushing structure of any container that applicant has knowledge of at the present time.

45 The plug or bung 14, illustrated in the present embodiment, has a head or flange portion 14a, the main body portion adjacent thereto being provided with threads 15 to engage the internally threaded body portion 12. The outer periphery of the flange of the bung 14 is preferably octagonal in shape and a square 50 recess 16 is formed in the head for engagement with a tool.

55 The plug 14 is preferably cast with a peripheral groove 17 beneath the flanged head portion and adjacent the threads 15, the groove providing a recess in which a cast material 18 is disposed. The cast material results in the formation of a sealing band and may be of lead or of a suitable material softer than the body portion 12 or bung 14. The 60 outer diameter of the sealing band is co-extensive with the outer diameter of the threads of the bung and tapers slightly outwardly from the container at its juncture therewith or, as shown in the drawings, upwardly therefrom. The threads of the body portion 12

form threads in the cast material in the recess when the bung is screwed into the flange. This provides a very effective seal for the container and the form thereof has been very accurately described in my copending application, Serial No. 232,722.

65 A lug 19 is preferably formed integrally with the plug 14 and has a depending portion 20 likewise preferably integrally formed thereon at the outer end thereof. For purposes of convenience, the lug 19 is shown as being substantially the width of one side of the octagonally shaped head portion of the bung, the depending portion being preferably of the same width. A slot or groove 21 80 is formed in the upper and lower surfaces of the lug preferably at the line of intersection with the plug to form a weakened portion, the use of which will hereinafter be more fully described. A hole 22 is formed in the plug 19 to receive a pin 23 in snug engagement therewith, the pin 23 being preferably round, although it is to be understood that any shape or form may be employed as desired.

85 The depending portion 20 is spaced laterally a short distance from the collar 11 of the socket to receive therebetween a vertically extending portion 24 of a tag 25. The vertically extending portion 24 has a horizontally extending portion 26 extending in the same direction as the tag proper and from the upper end thereof, the horizontally extending portion 26 being preferably of a width 90 to snugly fit in the space between the depending portion 20 and the collar portion of the socket.

95 In the assembly of the tag 25 with the elements of the bushing construction and the bung, the vertically extending portion 24 is disposed adjacent one of the edges of the polygonally shaped socket and the plug 14 is screwed into the container until the depending portion 20 of the lug 19 occupies a position adjacent the vertically extending portion 24 of the tag 25. The pin 23 is then inserted in the aperture 22 and is forced downwardly against the horizontally extending portion 26 of the tag 25, thereby upsetting or turning over the lip or horizontally extending portion 26 at that particular point whereafter a movement sidewise of the tag is not possible due to the remaining width of the horizontally extending portion remaining in a horizontal position.

100 In order to further guard against the unauthorized removal of the tag 25, the portions 27 extend beyond the upwardly extending portion 24 and are found to abut the adjacent edges of the hexagonal shaped plug 14 for a substantial distance around the periphery thereof. It is usual that the bung and the receiving bushing therefor be positioned adjacent the chime of the barrel and therefore the tag has been formed so as to be capable 105 110 115 120 125 130

of lying in the space between the bung 14 and the chime 28, the tag conforming to and lying adjacent the curvature thereof although it is to be understood that the body of the tag 5 may assume any position around the periphery of the bushing. As hereinbefore stated, this tag is for the purpose of identifying the contents of the container as for example the different grades of oil. Should 10 the tag 25 be removed and a less expensive oil be substituted for the oil originally contained in the container or should an attempt be made to replace the tag with another tag, the recipient of the barrel would be informed 15 by the tampering with the tag that access has been had to the oil since it has been in transit from the refiner.

20 However, in lieu of the tag 25, should access be had to the barrel as by means of removing the plug 14, such removal would be detected for the reason that in order to unscrew the bung 14, it would be necessary to break the lug 19.

25 It will be apparent, by referring to Fig. 3,
that in removing the bung, the pin 22 would
strike against one edge of the polygonally
shaped socket because of the fact that the edge
of the polygonally shaped socket is a tangent
to the circle around which the pin 22 would
30 move. By forcing the pin against the edge
of the polygonally shaped socket the tangent
or edge forms a cam surface against which
the pin rides and as it is moved over the cam
surface the lug is broken at the weakened
35 portion 21.

Referring now to Figs. 4 and 5 of the drawings, a modified form of this invention is shown in which a socket 11 is formed outwardly from a supporting wall 10 of a container to receive a body portion 12 in snug engagement therewith. As in the preceding construction, the body portion 12 is internally threaded to receive an externally threaded bung 14 having a sealing material 18 disposed in a groove 17 beneath the preferably octagonally shaped head portion thereof. A lug 19 having a depending portion 20 and a weakened portion 21 is likewise preferably formed integrally with the bung 14 and has an aperture 22 therein to receive a pointed pin 29. The tag 25 has a vertically extending portion 26, the upper end of the vertically extending portion being formed to extend horizontally as at 30 in a direction away from the tag proper to engage the outer surface of the flange of the socket. The vertically extending portion 26 of the tag 25 preferably rests against the edge of the socket 11, the distance between the horizontally extending portion 30 and the bottom surface of the tag 25 being less than the height of the socket 11. The tag 25 is assembled to this bushing structure in the manner described with reference to Figs. 1 to 3. However, in lieu of the pin deforming the horizontally extending

portion as provided heretofore, the pointed end portion pierces and projects through the tag proper, the outer diameter of the pointed pin 23 being preferably spaced from the outer edge of the socket 11 just a sufficient distance to permit the vertically extending portion 26 of the tag to lie therebetween in a clamped relation. 70

By reason of this pin urging the upward-
ly extending portion 26 against the socket,
the main body of the tag 25 will not give
as the pin 29 engages therewith but will per-
mit the pin to pierce therethrough. Thus
the tag 25 will not be permitted to be removed
by reason of the pin holding the tag, it being
further noted that the pin can not be gripped
from the top as it is preferably flush with
the top surface of the plug and cannot be
forced upwardly from below.

In the previously described embodiment, the pin 23 has been of a size such as to be protected from exterior access by the depending portion 20, the pin extending to within a short distance from the lower surface and being flush with the top surface thereof. Both the pins of these constructions are preferably of tool-hardened steel so that they cannot be drilled out of their respective openings. 25 30

Referring now more particularly to Figs. 6 to 10, inclusive, a further modification is shown wherein the supporting wall 10 of the barrel or container has an outwardly extending socket 11 for receiving in snug engagement therewith the internally threaded main body as in the previously described embodiments. An octagonally shaped bung 14 is adapted to engage the main body portion 12. However, in this instance, the sealing means as shown and described in the previous modifications have been omitted to show the ordinary washer 31 disposed between the flange of the bung 14 and the outer surface of the socket 11, flange 19 having a depending portion 20 and a weakened portion 21 formed on the flange of the bung 14, the depending portion 20 being spaced a substantial distance from the edge of the polygonally shaped socket.

As shown more particularly in Figs. 8 and 10, one end of the depending portion 20 has an extension 32 thereon which extends to within a very short distance of the edge of the socket. This latter distance is substantially the thickness of the vertically extending portion 33 of the tag 34. The upper end of the vertically extending portion 33 is formed at right angles thereto as at 34. A wedge 35 is forced into the space between the depending portion 20 and the vertically extending portion 33 of the tag 34, the wedge 35 being of a length to be entirely enveloped by the lug 19 and the depending portion 20 thereof. Inasmuch as the portion 32 extends across one end of the opening into which the wedge 35 is disposed, it is not pos-

sible to release the wedge by any other means than by breaking the extension 32 or by otherwise mutilating the lug 19.

In Fig. 7, it will be noted that the wedge 35 is of a square cross section and that the wedge in Fig. 9 has a similar cross section with the exception that one edge thereof is tapered to conform to the taper of the collar 11 of the socket and the edge of the main body portion 12. However, it is to be understood that various means may be employed as an obstruction to the travel of the lug 19 whereby a forcing of the plug 14 beyond such an obstruction would mutilate the plug such as by the breaking of the lug 19. The wedge 35 may be of any shape to conform with various contours of body portions and the like, and hence this application is not to be limited as to the specific construction. Further, the tags 25 and 34 may be formed into various shapes although it is preferable that they be held by the auxiliary means mentioned in this application in addition to the pins and wedges thus described.

While several embodiments of this invention have been herein shown and described, it is to be understood that various modifications thereof may be apparent to those skilled in the art without departing from the spirit and scope of this invention, and, therefore, the same is to be limited only by the prior art and the scope of the appended claims.

I claim:

1. The combination with a container having an opening therein, of closure means for said opening, said closure means being characterized thereby that it has an integrally formed weakened portion engaging a removable stop at which a fracture or break occurs upon a displacement of said means.

2. The combination with a container having an opening therein and connecting means adjacent said opening, of closure means engaging said connecting means, said closure means having an integrally formed weakened portion thereon, and engaging means between said connecting means and said weakened portion for causing a fracture or break upon a displacement of said connecting means.

3. The combination with a container having an opening therein and connecting means adjacent said opening, of closure means engaging said connecting means, said closure means having integrally formed projecting means thereon, and engaging means adjacent said projecting means for engaging a portion of said container, said projecting means having a weakened portion at which a fracture or break occurs upon a displacement of said closure means.

4. The combination with a container having a body portion adjacent a hole in a supporting wall thereof, of closure means engaging said body portion, projecting means

integrally formed on said closure means overlying an outer wall of said body portion and having a weakened portion, and engaging means between said projecting means and said outer wall, said projecting means engaging with said engaging means upon a displacement of said closure means whereby to effect a fracture or break at said weakened portion.

5. The combination with a container having a body portion adjacent a hole in a supporting wall thereof, of closure means engaging said body portion, a lug formed integrally with said closure means overlying an outer wall of said body portion and having a weakened portion, and engaging means between said lug and said outer wall, said lug having engagement with said engaging means upon a displacement of said closure means whereby to effect a fracture or break at said weakened portion.

6. The combination with a container having a body portion adjacent a hole in a supporting wall thereof, of closure means engaging said body portion, a lug formed integrally with said closure means overlying an outer wall of said body portion, and engaging means between said lug and said outer wall, said lug having engagement with said body portion upon a displacement of said closure means whereby to effect a fracture or break of said lug.

7. The combination with a container having an outwardly formed polygonally-shaped body portion adjacent a hole in a supporting wall thereof, of closure means engaging said body portion, projecting means formed integrally with said closure means adapted to overlie one side wall of said polygonally-shaped body portion and engaging between said projecting means and said side wall, said projecting means engaging said engaging means upon displacement of said closure means whereby to effect a fracture or break of said projecting means.

8. The combination with a container having a body portion adjacent a hole in a supporting wall thereof, of closure means engaging said body portion, engaging means adjacent said body portion and means formed on said closure means for engaging said engaging means whereby a displacement of said closure means effects a fracture or break therein.

9. The combination with a container having a body portion adjacent a hole in a supporting wall thereof, of a bung for engaging said body portion, and a pin disposed in said bung after said bung is in position in said body portion, said pin engaging said body portion to effect a fracture or break in said bung upon a displacement thereof.

10. The combination with a container having an outwardly formed body portion adjacent a hole in a supporting wall thereof,

- of a bung for said hole, said bung having an extension thereon overlying said body portion, and a pin disposed in said extension after said bung is in position on said body portion, said pin engaging to effect a fracture or break of said extension upon a displacement thereof. 11. The combination with a container having an outwardly formed body portion adjacent a hole in a supporting wall thereof, of a bung for said hole, a lug extending from and fixed to said bung having a depending portion adjacent the side wall of said body portion and spaced therefrom, and a pin disposed in said lug and lying between said depending portion and said side wall after said bung is in position in said body portion, said pin engaging said wall to effect a fracture or break in said lug upon a displacement of said bung. 12. The combination with a container having an outwardly formed body portion adjacent a hole in a supporting wall thereof, of a bung for said hole, a lug extending from and fixed to said bung having a depending portion adjacent the side wall of said body portion and spaced therefrom, said lug having a weakened portion, and a pin disposed in said lug at said weakened portion after said bung is in position in said body portion, said pin engaging said wall to effect a fracture or break in said lug upon a displacement of said bung. 13. The combination with a container having an outwardly formed body portion adjacent a hole in a supporting wall thereof, of a bung for said hole, a lug extending from and fixed to said bung having a depending portion adjacent the side wall of said body portion and spaced therefrom, and means disposed between said depending portion and said side wall after said bung is in position in said body portion, said means engaging said wall to effect a fracture or break in said lug upon a displacement of said bung. 14. The combination with a container having an outwardly formed polygonally-shaped body portion adjacent a hole in a supporting wall thereof, of a bung for engaging said body portion, a lug formed on said bung extending beyond the confines of said body portion, said lug having a depending portion adapted to lie adjacent one side wall of said polygonally-shaped body portion, and means disposed between said depending portion and said side wall after said bung is in position on said body portion, said means engaging said side wall to effect a fracture or break in said lug upon a displacement of said bung. 15. The combination with a container having an outwardly formed body portion adjacent a hole in a supporting wall thereof, of a bung for engaging said body portion, a lug formed on said bung overlying said body portion, means engaging said lug after said bung is in position on said body portion, and a tag held in a fixed relation with said body portion and said lug by said means whereby a displacement of said tag prevents a replacement thereof without said replacement being detected. 16. The combination with a container having an outwardly formed body portion adjacent a hole in a supporting wall thereof, of a bung for engaging said body portion, a lug formed on said bung overlying said body portion, means engaging said lug after said bung is in position on said body portion, said means extending adjacent the side wall of said body portion, and a tag held in a fixed position between said side wall and said means whereby a displacement of said tag prevents a replacement thereof without said replacement being detected. 17. The combination with a container having an outwardly formed body portion adjacent a hole in a supporting wall thereof, of a bung for engaging said body portion, a lug formed on said bung having a depending portion adapted to lie in a spaced relation with a side wall of said body portion, a tag having a portion thereof lying adjacent said side wall, and means engaging said depending portion after said bung is in position on said body portion, said means engaging and holding said tag in a fixed relation with said body portion and said lug whereby displacement of said tag prevents a replacement thereof without said replacement being detected. 18. The combination with a container having an outwardly formed body portion adjacent a hole in a supporting wall thereof, of a bung for engaging said body portion, means engaging said body portion after said bung is in position on said body portion, and a tag held in a fixed relation between said body portion and said means whereby a displacement of said tag prevents a replacement thereof without said replacement being detected. 19. The combination with a container having an outwardly formed body portion adjacent a hole in a supporting wall thereof, of a bung for engaging said body portion, a lug formed in said bung extending beyond the confines of said body portion, said lug having a depending portion adapted to lie adjacent a side wall of said body portion, a tag extending outwardly from said body portion beneath said depending portion, said tag having an end lying adjacent a side wall of said body portion, and means in said lug after said bung is in position on said body portion for deforming a portion of the end of said tag and for holding said tag against displacement without said displacement being detected. 20. The combination with a container having an outwardly formed body portion adjacent a hole in a supporting wall thereof, of a bung for engaging said body portion, a lug

- formed in said bung extending beyond the confines of said body portion, said lug having a depending portion adapted to lie adjacent and in a spaced relation with a side wall of 5 said body portion, a tag extending outwardly from said body portion beneath said depending portion, said tag having an end lying adjacent a side wall of said body portion, a pin in engagement with said lug and disposed 10 in the space between said depending portion and said side wall, said pin deforming a portion of the end of said tag and holding the same against displacement without said displacement being detected.
- 15 21. The combination with a container having an outwardly forward polygonally-shaped body portion adjacent a hole in a supporting wall thereof, of a bung for engaging said body portion, a lug formed on said bung 20 extending beyond the confines of said body portion, said lug having a depending portion adapted to lie adjacent one side wall of said polygonally-shaped body portion, and means disposed between said depending portion and 25 said side wall after said bung is in position on said body portion, said means engaging said side wall to effect a fracture or break in said lug upon a displacement of said bung, said means being prevented from exterior 30 access by said depending portion.
22. The combination with a container having an outwardly formed body portion adjacent a hole in a supporting wall thereof, of a bung for engaging said body portion, a lug 35 formed in said bung extending beyond the confines of said body portion, said lug having a depending portion adapted to lie adjacent a side wall of said body portion, a tag extending outwardly from said body portion 40 beneath said depending portion, said tag having an end lying adjacent a side wall of said body portion, said end extending a substantial distance around and adjacent to the periphery of said body portion, and means in 45 said lug after said bung is in position on said body portion for deforming a portion of the end of said tag and for holding said tag against displacement without said displacement being detected.
- 50 23. The combination with a container having an outwardly formed body portion adjacent a hole in a supporting wall thereof, of a bung for engaging said body portion, a lug formed in said bung extending beyond the 55 confines of said body portion, said lug having a depending portion adapted to lie adjacent and in a spaced relation with a side wall of said body portion, a tag extending outwardly from said body portion beneath said depending portion, said tag having an end lying adjacent a side wall of said body portion, a pointed pin in engagement with said lug and disposed in the space between said depending portion and said side wall, said pin penetrating a portion of the end of said tag and 60 65

holding the same against displacement without said displacement being detected.

24. The combination with a container having an opening therein, of closure means for said opening, projecting means formed on 70 said closure means, and engaging means between said projecting means and said closure means, said projecting means being fractured or broken upon a displacement of said closure means. 75

25. The combination with a container having an opening therein and connecting means adjacent said opening, of closure means for said connecting means, said closure means having projecting means integrally formed thereon, and engaging means adjacent said projecting means for engaging a portion of said container, said projecting means being fractured or broken upon a displacement of 80 said closure means. 85

In witness whereof, I have hereunto subscribed my name.

HENRY SCHWARTZ.

CERTIFICATE OF CORRECTION.

Patent No. 1,861,756.

June 7, 1932.

HENRY SCHWARTZ.

It is hereby certified that error appears in the printed specification of the above numbered patent requiring correction as follows: Page 4, line 95, claim 6, for "body portion" read engaging means; page 6, line 25, claim 21, for "bunk" read bung; and that the said Letters Patent should be read with these corrections therein that the same may conform to the record of the case in the Patent Office.

Signed and sealed this 4th day of October, A. D. 1932.
